CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS

ELECTRIC SWITCH

Original application filed April 2, 1923, Serial No. 629,252. Divided and this application filed October 28, 1927. Serial No. 229,513.

This application is a division of my co-pending application Serial No. 629,252, filed April 2, 1923.

This invention relates to oil immersed electric switches especially adapted for outdoor installations, although not necessarily limited to such use.

The switch embodying this invention has operating mechanism by which it can be closed, with automatic tripping means, and one of the objects is the provision of means whereby the switch, when automatically opened, is disconnected from the operating mechanism, or at least the greater portion thereof, so that the movable switch members can move to open position rapidly, unimpeded by the mass and inertia of the operating mechanism.

A yet further object is generally to improve the construction and operation of electric switches.

Fig. 1 is a side elevation of a three pole switch embodying my invention, the switch comprising the center pole being partially in section.

Fig. 2 is a front elevation of one of the switch units of Fig. 1.

Fig. 3 is a detail front elevation of an enclosing casing for the control mechanism of the switch.

Fig. 4 is a sectional detail along line 4-4 of Fig. 3, illustrating the relative position of the component parts of the control mechanism in switch-closed position.

Fig. 5 is a detail illustrating the relative position of the component parts of the switch control mechanism when tripped electrically.

Fig. 6 is a similar view illustrating the relation of the parts of the control mechanism when the switch is opened manually.

Fig. 7 is a view of the control mechanism adapted for manual control only, the dotted position of the mechanism illustrating the switch-open condition of the mechanism.

The switching apparatus here shown is adapted for the control of a three phase circuit and comprises three similar switch units. Each switch unit is so constructed and arranged that a switching apparatus adapted to control circuits of various phases may be

built up by assembling and connecting together in line a suitable number of switch units. Each switch unit may comprise a frame 20 of more or less rectangular shape, which frame is adapted to comprise a cover for the oil receptacle 21. Said oil receptacle is received within said frame and depends therebelow and may rest upon the cradle 22. Said cradle is secured removably to the switch frame by suitable means as the rods 23 and nuts 23a, whereby the oil receptacle is also secured removably to the switch frame. The top walls 24 of said switch frames are preferably inclined downwardly from the middle portion thereof and stationary switch members comprising the insulators 25 and the conducting studs 26 are inserted through said inclined walls and secured thereto. Said studs 26 are provided with screw-threaded lower end portions on which the main stationary contact members 27 are secured. Auxiliary stationary contact members 28 may be detachably secured to said main contact members 27 and are adapted to cooperate with the auxiliary contact members of the movable switch member in the usual manner.

Said switch frame 20 is provided with a transverse mechanism-containing compartment 30 disposed between the stationary switch members; and the side walls 31 of said compartment may be extended laterally in opposite directions beyond the body of the switch frame and may terminate in vertically extended flanges 32 and 33 which are adapted to be secured to similar flanges of adjacent switch units by suitable means as the bolts 34, whereby to tie together the various switch units and form a unitary switch structure.

The movable switch member may include the insulating rod 36 provided with the brush member 37 at the lower end thereof. A metal rod 38 is fixed to the upper end of said insulating rod 36 and extends slidably through an aperture in the bottom wall of the mechanism compartment and may carry a block 40 adjustably threaded on the upper end thereof. Said block 40 is disposed between and pivoted to the upper ends of

guide links 41 of the switch mechanism. The lower ends of said guide links are pivotally connected with the pair of strut links 42; and said latter links are pivoted on a 5 pin 43 extended through the opposite walls 31 of the mechanism compartment. A pair of bell crank levers 45 are pivotally mounted on a pin 46 extended through the opposite end of the side walls 31 of the mechanism 10 compartment and the long arms of said bell crank levers are pivotally connected by suitable means, as the pins 47, to an intermediate portion of the guide links 41. This construction and disposition of mechanism 15 provides means to guide the upper end of the movable switch member in substantially a straight line.

The various and similar switch units are adapted to be assembled together in line 20 and united with each other, as above described, by the bolts 34. The switch units may be supported on a suitable frame 50 and, for this purpose, the switch frames 20 may be formed or provided with the lateral 25 extensions 51 adapted to rest upon said frame 50. Bolts 52 may be passed through said extensions 51 into said frame 50 whereby to secure the switch units to said frame. The rear end of the mechanism compartment 30 of the rear switch unit may be closed, preferably removably, by suitable means as the cover plates 53.

The switch mechanisms of all the switch units are connected together for conjoint operation by the two spaced bars 55 which are 35 extended through the upper portion of the connected mechanism compartments of the switch units and are pivotally connected with the short arms 45a of the bell crank 40 levers 45 of the separate switch mechanisms.

The switch operating or control mechanism is adapted to be contained mainly within a separate casing 60 which is secured against the free flange of the foremost 45 switch unit. Said casing 60 is divided into an upper compartment 61 adapted to contain switch operating mechanism, two spaced intermediate compartments 62 and 62a adapted to contain the tripping coils. Said casing is also formed with a central 50 vertical passage 64 which is in communication with the upper compartment 61 and is adapted to contain a member of the operating mechanism adapted to provide for the manual control of the switch. Said various 55 compartments may be closed by the cover plates 65 and 66 and said cover plates may be secured removably in position by any suitable means as the thumb nuts 67.

The switch mechanism herein illustrated 60 is adapted to provide for the manual open-

ing and closing of the switch and also for the automatic tripping of the switch by electrically controlled tripping means.

The switch operating mechanism includes a pair of spaced bell-crank levers 70 which are 70 disposed between the bell-crank levers 45 of the foremost switch unit and pivotally supported on the pivot pin 46 of said bell crank levers. The upper arms 70a of said bell crank levers are pivotally connected by the 75 pin 72 to triangularly shaped and spaced plates 73 which constitute members of a locking toggle for all of the switch units. A link 74 is disposed between said plates and pivotally connected to said plates by suitable means as the pin 75. The other end of said link may be disposed between the arms 45a of said foremost bell crank levers 45 and pivotally connected thereto by the pin 76. The connections between said link 74 and the bell 80 crank levers 45 and the plates 73, and between said plates 73 and the bell-crank levers 70 are adapted to be such as to form an inverted toggle which when substantially in an on-center position is adapted to hold the switch units closed. A latch roller 78 is disposed between the lower ends of said plates 73 and rotatably supported on a pin 79 passed through said plates. A latch 80 may be disposed between said plates and pivotally supported on the pin 46. Said latch is arranged to engage said cam roller 78 and releasably hold the inverted toggle and consequently the switch closed; and said latch is adapted to be raised whereby to release said cam roller and permit the toggle to be broken by the weight of the movable switch member, or accelerating springs 89, whereby to permit the switch to open. Said latch 80 is adapted to be raised to trip the switch by means including the 90 link 82 which is disposed beneath said latch and is formed or provided with an elongated slot 83 in which the fixedly supported pin 82a is received. Said pin 82a is adapted to guide said link 82 in the tripping movement thereof. Said link 82 is pivotally connected at its lower end to the forwardly extended arm of a tripping frame 84. Said frame is pivotally supported by the fixed brackets 85 and has laterally extended extensions or arms 86 95 through which pins 87 may be adjustably extended for engagement with tripping members of the tripping coils.

The tripping coils are adapted to be contained in the compartments 62 and 62a and disposed beneath the tripping frame 84. Each tripping coil may comprise the coil bobbin 90 in which a tube 91 may contain the plunger of the coil. Said tube 91 may be formed or provided with a reduced upper end portion 92 which is adapted to be extended through an aperture in the top compartment 61 and a nut 93 may be threaded on said reduced portion 92 whereby to secure said tube 91 and consequently the coil bobbin in place. 100

Each coil compartment may contain a plurality of, as two, coils. Tripping pins 94 may be slidably extended through said tubes 91 into the top compartment and are adapted 5 to be engaged by the movable plungers. A tripping plate 95 is extended between and pivotally received or fulcrumed on each pair of tripping pins and the arrangement is such that each coil may act independently to raise 10 said tripping plate to trip the switch or the coils may act conjointly to trip the switch.

The lower or calibration ends of the tubes 91 of said tripping coils are extended slidably through the bottom walls 97 of the coil compartments and into the lowermost compartments 15 63 and 63a and adjustments of the current settings of said coils may be made in these compartments. The bottom walls 98 of said lowermost compartments are formed 20 with apertures therein which are aligned with the tube apertures in the upper wall 97. The trip coils may be removed from their enclosing compartments by first withdrawing the tubes 91 through said aligned apertures. 25 Said apertures in said lowermost walls 98 are normally closed by the plugs 99.

The switch operating components adapted 30 to provide for the manual opening and closing of the switch include the pairs of links 105 which are pivotally connected to the lower arms 70b of the bell-crank lever 70. Said links 105 are also pivotally connected by suitable means as the pivot pin 106 with a pair of links 107 and said links 107 are in turn pivotally supported on the fixed pin 82a. Said 35 pairs of links 107 and 105 constitute toggle members adapted to be actuated manually to effect the opening and closing of the switch. A link 108 is disposed between said links 105 40 and 107 and pivotally supported on the pivot pin 106. The lower end of said link is pivotally connected to the connecting bars or rods 110 which extend downwardly through the central passage 64 of the casing. The 45 lower ends of said bars 110 are adapted to be pivotally connected to an operating handle 111 and said handle is pivoted to a bracket 112 secured to the lower wall 98 of the casing 60.

50 When the switch is closed, the switch operating mechanism is in a position similar to that illustrated in Fig. 4. When the mechanism is tripped electrically, the bell-crank levers 70 and the toggle comprising the 55 links 107 and 105 and the operating handle 111 are adapted to remain stationary and said members will be held in such position by the toggle links 107 and 105 which toggle is adapted to be in somewhat over-shot position and in contact with a stop-member as the pin 113. With this arrangement, the upper arm 70a of the bell-crank lever 70 forms a 60 pivotal support for the toggle comprising the plates 73 and the link 74. When the 65 over-load coils are energized to trip the

switch, the latch 80 is raised from holding engagement with the latch roller 78 carried by the lower end of the plates 73 and, inasmuch as the toggle including said plates as a member is in a slightly under-shot position, the weight of the switch members, or accelerating springs associated therewith, serves to move the movable switch members rapidly into open position.

The switch-open position of the mechanism when tripped electrically is similar to that illustrated in Fig. 5. It is to be noted that with this arrangement, the only part of the operating mechanism that moves is the toggle comprising the plates 73 and the link 74. Inasmuch as said toggle may have very little weight and inertia, this arrangement provides a switch having a relatively high rate of opening movement.

As here shown, the switch is arranged to 25 be closed manually after it has opened electrically. For this purpose the handle is adapted to be raised whereby to break the toggle comprising the links 107 and 105 and rotate the bell-crank lever 70 in a clockwise 30 direction. This movement causes the plates 73 to rotate in a counterclockwise direction whereby to move the latch roller 78 into holding engagement with the latch 80. The connection between the switch operating 35 mechanism and the movable switch mechanism is thereby restored and when said operating handle 111 is moved downwardly, the operating mechanism is restored to a condition illustrated in Fig. 4.

When the switch is opened manually, the handle 111 is raised as before and the bell crank levers 70 remain connected with the switch mechanisms through the latch 80 to effect the manual opening of the switch and 40 remain connected therewith when the operating handle 111 is moved downwardly to effect the manual closing of the switch.

The switch mechanism herein illustrated 45 may also be arranged solely for manual opening and closing and the switch mechanism so arranged is illustrated in Fig. 7. For this arrangement, the toggle comprising the plates 73 and link 74 may be removed and a link 115 may be connected between the pivot pin 72 carried in the arms 70a of the bell-crank levers 70 and the pivot pin 76 carried in the arms 45a of the bell-crank levers 45. This arrangement serves to connect said bell-crank levers 70 fixedly to the 50 bell-crank levers 45 whereby the operation of said handle 111 serves to open and close the switch units; and the switch units will remain in closed position until the handle is moved downwardly as the toggle comprising 55 the members 107 and 105, in the switch closed condition, is adapted to be in slightly over-shot position.

I claim:

1. An electric switch comprising the com- 130

- bination of a movable switch member, a guide link pivoted at one end thereto, a pivotally supported strut link pivoted to the other end of said guide link, a bell crank lever having 5 a fixed pivotal support and a pivotal connection with said guide link for operating it, a second bell crank lever pivoted concentrically with said first bell crank lever, a toggle connecting said bell crank levers, a second toggle 10 arranged to actuate said second bell-crank lever to open and close the switch through said first toggle and hold said first bell-crank lever against operation, a latch arranged to hold said first toggle releasably in set condition 15 whereby to permit the switch to be closed by said second toggle, and means to trip said latch, whereby to release said first toggle and permit the switch to open independently of said second bell crank lever and second toggle.
- 20 2. An electric switch comprising the combination of relatively movable switch members, switch-operating mechanism including a pivoted lever, and control mechanism for said switch-operating mechanism including a bell-crank lever, means operatively connecting said bell crank lever and pivoted lever including a link pivotally connected with both levers, a toggle arranged to actuate said bell-crank lever, and manually-operable actuating means for said toggle.
- 25 3. An electric switch comprising the combination of a switch frame, relatively movable switch members carried thereby, switch operating mechanism including an operating lever pivoted to said frame, control mechanism for said operating mechanism including a bell-crank lever supported on the pivot of said operating lever and extended outwardly beyond said switch frame, links constituting 30 a toggle connecting said bell-crank lever and operating lever, a latch pivotally supported on the pivot of said operating lever and extended outwardly beyond said switch frame arranged releasably to hold said toggle in 35 set condition, whereby to permit said bell-crank lever to open and close the switch through said toggle, means to trip said latch whereby to release said toggle and permit the switch to open independently of control 40 by said bell-crank lever, means to operate said bell-crank lever including a second toggle connected therewith and arranged to be restrained in set position whereby releasably to hold the switch closed, and means to 45 operate said second toggle.
4. An electric switch comprising the combination of relatively movable switch members, switch operating mechanism, control mechanism therefor including a pivoted 50 member, a plate pivoted to said pivoted member, a link pivoted to said plate and to a member of said switch-operating mechanism, said plate and link arranged to form an inverted toggle whereby releasably to hold the 55 switch closed, said plate having a projection 60 disposed below the pivotal connection of said link and pivoted member, a pivoted latch arranged to engage said projection and hold said toggle releasably in set condition in switch open and closed positions and release 65 said projection in the switch closed position of the toggle, whereby to permit the toggle to be broken and open the switch, tripping means for said latch, and operating means for said pivoted member including a second 70 toggle arranged to be restrained in switch closed position, and operating means for said second toggle.
- 75 5. An electric switch comprising the combination of relatively movable switch members, switch operating mechanism including a pivoted lever, a pivoted member, means including a toggle connecting said lever and member, a latch arranged releasably to hold 80 said toggle in set condition, a second toggle connected with said pivoted member, actuating means for said second toggle, and latch tripping mechanism including a pivoted tripping frame disposed below said latch, a slotted link pivotally connected with said frame and extended upwardly under said latch and a guide pin arranged in the slot in said link, whereby to guide said link for 85 vertical latch-tripping movement.
- 90 In testimony whereof, I have signed my name to this application.
